Specification of Letters Patent.

Patented Feb. 8, 1916.

Application filed September 29, 1911. Serial No. 651,908.

To all whom it may concern:

Be it known that I, HARRY SHOEMAKER, a citizen of the United States, residing at Jersey City, county of Hudson, and State of New Jersey, have invented a new and useful Signaling Apparatus, of which the following is a specification.

My invention relates to signaling apparatus, and more particularly to apparatus employed in space signaling such as wireless telegraphy, wireless telephony, and the like, in which electro-radiant energy represents the signals or messages in transmission through space.

5 More particularly my invention relates to improved transmitting apparatus wherein a spark gap of peculiar construction is used for the production of the electrical oscillations used for transmitting messages.

10 In most wireless telegraph systems used at the present time a spark gap is used for the production of electrical oscillations, said spark gap being operated in an exposed manner or in inclosed spaces. In some cases the spark gap is operated under a pressure greater than that of the atmosphere, and in other cases a blast of air is forced across the spark gap continuously during its operation for the purpose of quickly establishing its normal condition.

The function of the spark gap is well known in the art at the present time and briefly stated, is for the purpose of establishing a good conducting path for the electrical oscillations after the condenser in the oscillating circuit has been charged to a certain critical value. When, however, a number of discharges take place across the spark gap in rapid succession the intervening air or gases are heated and dissociated in such a manner as to prevent the rapid return to normal conditions. This has been obviated to a certain extent by the above mentioned means; *i. e.*, by inclosing the gap and subjecting it to a greater pressure than that of the atmosphere and also by means of forcing an air blast through the spark gap. In my invention I produce this effect by an entirely new and novel means, *i. e.*, by introducing a solid dielectric in the spark gap immediately after each discharge of the condenser, or, in other words, after each spark. With this method it is not necessary to remove the heated or ionized air or to inclose the spark gap and subject

it to a pressure, as the insertion of the solid dielectric produces the same effect in a much more constant manner.

For an illustration of some of the forms my invention may take reference is to be had 60 to the accompanying drawings, in which—

Figure 1 is a diagrammatic view of one of the forms which my invention may take, Fig. 2 is a diagrammatic view of a modified form of the same invention, Fig. 3 is a fragmentary view of illustrating the means which I provide for the rotation of the disk which is constructed of a dielectric or non-conducting material; Fig. 4 is a diagrammatic illustration of another modification of 70 my invention; Fig. 5 is a plan view of the rotating disk of dielectric material showing holes arranged on a circle concentric with the periphery of the disk, and the relative relation of the spark gap and air nozzle is used 75 to produce its rotation; Fig. 6 is a diagrammatic view of another form which the invention may take.

In Fig. 1, 20 is an alternating current generator or other suitable source of energy, 21 80 is a signaling key or circuit breaker, 22 is the primary of the transformer. The generator 20, key 21, and primary 22 are connected in series so that key 21 controls this circuit. 23 is the secondary of the transformer and 85 has its terminals connected to the condenser 13. 12 is an inductance which can be varied by means of the contact or clip 15. 11 is a conductor which connects contact 15 and spark gap terminal 10. The spark gap terminal 9 is connected by means of conductor 14 to one of the terminals of the condenser 13, the other terminal of this condenser being connected to the fixed terminal of inductance 12. The axes of spark gap terminals 9 and 90 10 coincide. 6 is a disk constructed of a non-conducting or dielectric material such as glass, slate, mica or porcelain. This disk is mounted on the shaft 3 between the collars 4 and 5. The shaft 3 rotates in the bearings 100 1 and 2. Around this disk on a circle concentric with its periphery a number of holes are bored through it. These holes are so situated that their centers successively coincide with the axes of the spark gap terminals 9 and 10 when said disk is rotated. A tube or nozzle 8 is directed at such an angle to the face of the disk that when air or other gases is forced through it, it causes 105 the disk 6 to rotate at a speed depending 110

- on the pressure of said air or gases. 16 is the aerial or radiating conductor, 17 is an inductance which may be varied by means of the clip or contact 18 which in turn is connected to the ground 19. The radiating conductor 16, inductance 17 and ground 19 are in series and will hereafter be called the radiating circuit. The circuit including condenser 13, inductance 12, conductor 11, spark gap terminals 9 and 10, and conductor 14 will hereafter be called the exciting circuit. The secondary 23 and its connections will hereafter be called the charging circuit.
- 15 In Fig. 3, 6 represents a fragment of the disk, 7 one of the holes, and 8 the nozzle for directing the air jet against said disk which causes its rotation. In practice a number of these nozzles may be used so arranged that 20 at least one or more jets are directed against a hole for any position of the disk. This insures its prompt rotation when the air pressure is turned on. The air used for rotating this disk may be furnished by any 25 suitable pump, but most conveniently by means of a positive pressure blower or rotary pump giving from two to four pounds pressure and sufficient quantity to cause rotation at the proper speed.
- 30 Referring again to Fig. 1, the operation is as follows: The condenser 13 is charged by means of the charging circuit which causes the potential between the spark gap terminals 9 and 10 to rise to such a point that it 35 will discharge between said terminals providing one of the holes in the disk lies between said terminals. If, however, a solid portion of this disk lies between the said terminals it will be necessary for the potential to increase to such a value as to discharge over the surface of said disk. Now, if this disk is in rapid rotation the holes and solid portion of the disk are alternately presented between the spark gap terminals 40 9 and 10 in such a manner that the discharge only takes place when said holes pass between the terminals 9 and 10. The speed of the disk must be of a proper value or have a definite relation with the rate at 45 50 which the charging circuit furnishes energy to the condenser 13 in order to get a uniform strength of oscillation in the exciting circuit. If the disk should rotate too slowly the spark would tend to discharge over its surface and would consequently be longer and require a greater potential. If, however, the interval of time required for the solid portions of the disk to pass between the terminals 9 and 10 has the 55 proper value the successive charging potentials will be uniform and consequently the successive oscillations will be uniform. It will be readily seen that while the charging circuit may have a frequency of, say, 60 60 cycles, that is, the condenser 13 will be

charged 120 times per second, the number of discharges between the spark gap terminals 9 and 10 may greatly exceed this amount: for instance, if four holes pass between the spark gap terminals 9 and 10 in 1/120 of a second, there would be four distinct sparks or discharges during this time. This would have the same effect as far as the number of wave trains radiated per second is concerned as a primary frequency of 240 cycles. This high spark frequency is of great advantage in wireless telegraphy on account of the more agreeable note produced in the receiving apparatus: but the main advantage to be gained by this invention is the uniform manner in which the successive wave trains are produced, due to the fact that a solid dielectric is used instead of the more variable gas dielectric as used in present wireless telegraph systems.

While I have shown a method of rotating the disk by means of air or gas under pressure, any other convenient means can be employed, such as electric motors, either directly connected to the disk or by means of a belt.

In Fig. 5, 6 represents the disk, 7 the holes through which the spark passes, 9 shows the position of the spark gap terminals, 8 is the air nozzle for rotating the disk, and 3 is the hole through which the shaft passes. Fig. 5 taken in connection with Fig. 3 plainly shows the means for rotating the disk and the relative positions of the spark gap, air nozzle and holes in the disk.

Fig. 2 is substantially the same as Fig. 1 with the exception that provision is made for operating two spark gaps in series. In this figure the generator, key and transformer are not shown. 13 is the condenser, 12 the inductance, 15 the variable contact, 9 and 10 the end spark gap terminals, 24 is the intermediate terminal lying between the two disks 6 and 6', 14 is a conductor connecting spark gap terminal 9 with terminal of condenser 13. The disks 6 and 6' are mounted on the shaft 3 by means of collars 4, 5, 4' and 5'. Shaft 3 is mounted in the bearings 1 and 2, which permit its rotation. 8 is an air nozzle so constructed that it directs a jet of air on both disks 6 and 6'. 25 is a tube connected with the air nozzle 8 and with the air supply pipe. 7 and 7' are holes in the disks which allow the spark to take place when they pass between the terminals 9, 10 and 24. 16 is the radiating conductor, 17 is an inductance which may be variable, and 19 is a ground connection and, as in Fig. 1, this will hereafter be called the radiating circuit. The circuit including the condenser 13, inductance 12, spark gap terminals 9, 10 and 24 and conductor 14, will, as in Fig. 1, hereafter be called the exciting circuit. In both Fig. 1 and Fig. 2 the radiating circuit and the ex-

citing circuit are in inductive relation with each other.

In Fig. 4 23 is the secondary of a transformer and with its terminals forms the 5 charging circuit, and is connected to the terminals of condensers 13 and 13', which are connected in series with reference to the secondary 23. Condensers 13 and 13' are connected in series with the spark gap terminal 10, intermediate terminal 24, spark gap terminal 9. The inductance 12, which may be 10 variable, is connected between the condensers 13 and 13' and to the intermediate terminal 24. This forms two closed oscillating or 15 exciting circuits, the inductance 12 being common to both. The condenser 13, inductance 12, intermediate spark gap terminal 24, spark gap terminal 9, and their connecting conductors, form one of the exciting circuits, condenser 13', spark gap terminal 10, intermediate spark gap terminal 24, and inductance 12, with their connecting conductors form the other exciting circuit. The 20 disks 6 and 6' are mounted on the shaft 3 by means of collars 4, 5, 4' and 5'. The shaft 3 is mounted in bearings 1 and 2, which permit its rotation. 8 and 25 are air nozzles similar to that shown in Fig. 3. 7' is the holes in the disks. Both these disks 25 have the same number of holes, but the disks are so mounted on the shaft that when the disk 6' has one of its holes presented between spark gap terminal 9 and the intermediate terminal 24, the solid part of disk 6 is presented 30 between spark gap terminal 10 and intermediate terminal 24. This allows the discharge first to take place between spark gap terminal 9 and intermediate terminal 24, and then between spark gap terminal 10 and intermediate terminal 24. This allows 35 first the condenser 13 to discharge between the spark gap terminal 9 and intermediate terminal 24 and then the condenser 13' to discharge between spark gap terminal 10 and intermediate terminal 24, thus causing 40 the exciting circuits to operate alternately. The object of this is to enable the use of a greater amount of energy with the same potentials than could be used with a single 45 disk and one exciting circuit. It also permits the production of a greater number of wave trains per second than could be produced with one set of spark gap terminals and one exciting circuit. The radiating 50 conductor 16, inductance 17, which may be variable, and the ground connection 19, will hereafter be called the radiating circuit, and is in inductive relation with the exciting circuits.

In Fig. 6, 16 is a radiating conductor, 17 a variable inductance, 9 and 10 are spark gap terminals, and 19 is a ground connection. 6 is a disk of non-conducting material mounted on shaft 3 by means of collars 4 and 5. Shaft 3 is mounted in bearings 1 and

2 to permit its rotation, which can be accomplished by means of an air jet as in Figs. 1, 2 and 4, or by any other convenient means. In this case the exciting circuit and radiating circuit are combined in one and the 70 charging circuit or transformer secondary would be connected to the spark gap terminals 9 and 10. The holes 7 are successively passed between the spark gap terminals 9 and 10 in the same manner as shown in Figs. 75 1, 2 and 4. With a wireless telegraph system as shown in Fig. 6 this disk is of great value, due to the fact that the capacity of the oscillating circuit in this case is extremely small and when the system is charged by a transformer an arc is always produced between terminals 9 and 10, which practically prevents the production of electrical oscillations in the radiating circuit. Experience has shown that it is almost impossible to produce a great number of wave trains per second with this form of a wireless telegraph transformer. However, with the rotating disk as shown this trouble is prevented and 80 regular and uniform discharges at a high 85 rate can be produced.

While I have shown a number of forms which this invention may take, I do not wish to limit myself to any of the particular forms, and it is to be understood that the 95 real departure from the prior art is the use of a solid dielectric in the spark gap of the wireless telegraph transmitter instead of the fluid dielectric.

What I therefore claim is:

1. In a wireless telegraph transmitter, the combination of a high frequency oscillatory circuit having discharge terminals separated by a spark gap, and means for presenting alternately a solid dielectric and a fluid dielectric between said terminals for the purpose of regulating the sparking and intermittently clearing the gap of heated gases. 100

2. In a transmitter of electromagnetic waves, the combination of a high frequency 110 oscillatory circuit having discharge terminals separated by a spark gap, and means for intermittently presenting a solid dielectric between the terminals of said spark gap, for the purpose of regulating the sparking and intermittently clearing the gap of heated gases. 115

3. In a producer of electro-magnetic waves, the combination of a plurality of sets of terminals separated by spark gaps, means 120 for causing high frequency disruptive discharges across said gaps, and means for alternately presenting a solid dielectric and a fluid dielectric between the terminals of said spark gaps, for the purpose of regulating the sparking and intermittently clearing the gaps of heated gases. 125

4. In a transmitter of electromagnetic waves, the combination of a plurality of sets of terminals separated by spark gaps, 130

means for causing high frequency disruptive discharges across said gaps, and means for successively presenting a solid dielectric between the terminals of said spark gaps to 5 intermittently clear the gaps of heated gases.

5. In a producer of electro-magnetic waves, the combination of a high frequency oscillatory circuit having terminals separated by a spark gap, a rotary disk of non-conducting material, said disk being so constructed as to present intermittently a solid dielectric between the terminals of the spark gap, and means for rotating said disk, for the purpose of intermittently clearing the 10 gap of heated gases.
15. In a producer of electro-magnetic

waves, the combination of a plurality of sets of terminals separated by spark gaps, means for causing high frequency disruptive discharges across said gaps, and means for 20 successively presenting solid dielectrics between the terminals of said spark gaps, said solid dielectrics being presented between the terminals of the several sets in rotation.

In testimony whereof, I have hereunto 25 affixed my signature in the presence of the two subscribing witnesses.

HARRY SHOEMAKER.
